UNITED STATES PATENT OFFICE

OLGA H. WHITE, OF NEW YORK, N. Y.

DESIGN FOR A GAME DEVICE

Application filed June 18, 1929. Serial No. 31,741. Term of patent 14 years.

To all whom it may concern:

Be it known that I, OLGA H. WHITE, a citizen of the United States, residing at New York, in the county and State of New York, United States of America, have invented a new, original, and ornamental Design for Game Device, of the which the following is a specification, reference being had to the accompanying drawing, forming parts hereof.

Fig. 1 is a front elevation of a game device showing the new design; and

Fig. 2 is a side elevation of the design.

I claim:

The ornamental design for a game device as shown.

OLGA H. WHITE.
